UNITED STATES PATENT OFFICE.

GEORG HEINTZE, OF HANOVER, GERMANY.

MACHINE FOR DRAWING WOOL OR OTHER TEXTILE FIBER MATERIALS.

Application filed May 11, 1927, Serial No. 190,553, and in Germany May 15, 1926.

The present invention has for its object a machine for washing wool and other textile materials, in which the opening, cleaning and drawing procedures are performed 5 within a bath or washing-vat.

In the machines known up to now for opening such materials in a wet state, opening-cylinders are used carrying thick teeth allowing neither a restless opening of the 10 staple nor a release of vegetable impurities by drawing nor a thorough rinsing of the fleece, for the reason that the latter travels along with the working-surfaces of the rotating cylinders closely arranged one behind 15 another; during this travelling the fleece can be drawn or stretched very little only and, in consequence of the defective guide, cannot be drawn systematically, and partly leaves the bath together with the cylinders. 20 Pairs of drawing-cylinders proper as used in the drawing-gill-set ensuring a great drawing and safely releasing the burs of the needle-field, have not heretofore been provided. The coarse teeth the great distances 25 of which are necessitated by the bulky strip-devices are not suitable to retain burs; on the contrary they allow the burs to pass through the teeth together with the wool. Consequently said burs can be separated on 30 the carding-machine only.

The machine forming the object of the present invention has for its purpose to avoid the drawbacks mentioned above by the use of several drawing-gill-sets arranged in 35 rear of one another, the working surfaces of which are situated below the level of the liquid, so that the wool is, during the opening and drawing procedures, permanently situated within the liquid and is horizontally passed through the drawing-gill-set. 40 By these means a very careful opening and drawing of the wool-hair surrounded by a moist soap and grease-layer is ensured and the possibility is given to rinse the fleece held within the gill-field from above to be 45 below or vice versa without causing tangles of the hairs or fibers. The straightening procedure of the hairs or fibers in a wet state is a more perfect and more preserving one 50 than in the dry state, for the reason that the qualities as to plasticity of the wet fibers are very much better. The vegetable impurities, especially burs, are practically freed or released by the manner of drawing 55 procedure described, owing to the special nature thereof. Said impurities are situated

within the gill-field in the fleece between the gills; the close pitch of or small distance between the latter causes that the burs can not pass through the gills notwithstanding 60 the drawing or stretching. The hairs or fibers embracing the burs are retained behind the latter in consequence of the advancing movement of the gills, for the time during which the fibers are held between 65 the feeding rollers; the remaining part of the fibers advances to the burs as soon as it enters into the range of delivery. The stream of water sweeps away, besides the grease or dirt freed by the washing effect 70 of the bath and the squeezing action taking place between the cylinders, also freed or released vegetable particles from the range 75 of work in the direction of the said stream of water.

The use of several drawing-gill-sets arranged in series makes it possible to double the wool or the woolen fleece to be worked inasmuch as it is not only to be opened between the single pairs of drawing-gill-sets, 80 without any interruption of the work, said doubling being obtained by fleece-layers known per se, and to increase the drawing effect in the single drawing-gill-set in such a manner that the ribbon or sliver leaving 85 the last pair of gill-sets can, after the removal of the burs by known disintegrating cylinders and after drying and softening procedures, immediately be fed in the shape of a roving to the combing-engines or to the spinning-machines, simultaneously dispensing with the carding-machines. The carrying into effect of fine drawing-procedures of this kind and the cleaning procedure of 90 vegetable mixtures enabled thereby are not possible in the machines heretofore known and arranged with rotating opening-cylinders, in view of the very insufficient drawing effect as explained above; furthermore the doubling procedure is not possible without any interruption of the work, so that a feed of the ribbon or sliver to combing or spinning machines is not possible in the doubling procedure mentioned, whereas said feed is possible in the machine arranged according to the present invention. 95

The drawing annexed to the description represents as an example of construction the object of the present invention.

Fig. 1 is a longitudinal section of the left hand side of the machine, Fig. 1^a also in section the right hand side of said machine

and Fig. 2 shows diagrammatically the further treatment of the wool-fleece after having left the machine shewn in Fig. 1.

a. Fig. 1, is the washing machine proper filled with any suitable liquid (soap-suds or other extractive means) up to the dotted and dashed line. b is an endless band to which the wool deprived of grease in the extracting apparatus, for instance of system Mallard, or in any other suitable manner is fed to be carried to the first drawing-gill-set c. An endless rubber-band d is arranged in rear of said gill-set c and serves to feed the wool-fleece drawn in the first gill-set c to a doubling device f, after having passed through a pair of squeezing cylinders e. Said doubling device is diagrammatically shown and consists of a known device for laying the fleece in longitudinal direction and for supplying a continuous fleece. The doubled fleece having left the laying device enters into a second drawing-gill-set c₁. According to want, three or four of such drawing-gill-sets arranged in series and between each two gill-sets pairs of squeezing-cylinders e₁ and e₂ and doubling devices f₁ and f₂ and so forth may be provided.

During the drawing procedure effected within the liquid, the burs and other vegetable impurities are retained in the gill-field. The fibers or hairs entangling said burs are drawn in a forward and backward direction so that the burs and particles are freed and remain back on the wool fleece, from which they can afterwards be removed by burring-willows. To get a more intense effect of the washing-procedure and to remove the vegetable impurities freed between the gills from the wool fleece, a stream of water may be passed in a vertical or nearly vertical direction through said fleece held in the gill-field. This can be done, for instance, in such a manner that either a stream of water is directly passed through the gills from above in a downward direction or vice versa by a pump, represented generally at p, or the liquid is fed in a cycle through the gill-field in the direction indicated by arrows. The liquid is purified by passing it through fine sieves s and partly improved by an additional supply of liquid from any suitable source, as may readily be understood. The liquid purified in this manner flows over the partitions and back again to the gill-fields.

The fleece after having left the last pair of squeezing-cylinders e₂ and spread in a thin layer can be fed through rollers h, h₁, h₂, h₃ arranged, for instance, within a chamber, as diagrammatically shown in Fig. 2. A stream of warm air, g, can be blown through said rollers for the purpose of drying the fleece. Without any regard to the wool becoming electric later on, said drying procedure can be continued to such a degree that

the vegetable impurities become completely brittle and can easily be disintegrated or broken by the disintegrating cylinder, the so-called harmel i, to be hereafter removed from the wool-fleece whilst passing the cylinders h₁, h₂, h₃ by another intense stream of air. By the addition of a finely atomized softening material to this stream of air l the latter can perform the softening of the ribbon or silver and be kept so moist that the wool is again brought to that degree of moisture which is necessary for its further treatment.

The wool-fleece drawn and cleaned in the manner described can be fed to the combing-machine thus dispensing with sets of carding-machines, or it may be used also as a fine roving for certain requirements of long wool spinning or card-yarn-spinning.

What I claim is:

1. A machine for drawing wool and other textile fiber materials in which the said materials are drawn within a washing vessel, said machine comprising a plurality of drawing-gill sets arranged in series and having their working surfaces situated below the level of the liquid in said vessel. 85

2. A machine for drawing wool and other textile fiber materials in which the said materials are drawn within a washing vessel, 95 said machine comprising a plurality of drawing-gill sets arranged in series and having their working surfaces situated below the level of liquid in said vessel, and means for causing a flow of liquid in a substantially vertical direction through the material in the drawing-gill sets. 100

3. A machine for drawing wool and other textile fiber materials in which the said materials are drawn within a washing vessel, 105 said machine comprising a plurality of drawing-gill sets arranged in series and having their working surfaces situated below the level of liquid in said vessel, and means arranged between adjacent drawing-gill sets 110 for doubling and laying the material as it passes from one drawing-gill set to the next.

4. A machine for drawing wool and other textile fiber materials in which the said materials are drawn within a washing vessel, 115 said machine comprising a plurality of drawing-gill sets arranged in series and having their working surfaces situated below the level of liquid in said vessel, means for causing a flow of liquid in a substantially vertical direction through the material in the drawing-gill sets, and means arranged between adjacent drawing-gill sets for doubling and laying the material as it passes from one drawing-gill set to the next. 120

5. A machine for drawing wool and other textile fiber materials in which the said materials are drawn within a washing vessel, said machine comprising a plurality of drawing-gill sets arranged in series and hav- 125

ing their working surfaces situated below the level of liquid in said vessel, means adjacent the last said drawing-gill set for drying and flattening the material, and rolls adjacent the drying and flattening means for disintegrating burs in the material.

6. A machine for drawing wool and other textile fiber materials in which the said materials are drawn within a washing vessel, 10 said machine comprising a plurality of drawing-gill sets arranged in series and having their working surfaces situated below the level of liquid in said vessel, means for causing a flow of liquid in a substantially

vertical direction through the material in the 15 drawing-gill sets, means arranged between adjacent drawing-gill sets for doubling and laying the material as it passes from one drawing-gill set to the next, means adjacent the last said drawing-gill set for drying and 20 flattening the material, and rolls adjacent the drying and flattening means for disintegrating burs in the material.

In testimony, that I claim the foregoing as my invention, I have signed my name 25 this 10th day of March, 1928.

DR. ING. GEORG HEINTZE.
